SCISSOR

Maurice L. Cohn, New York, N. Y., assignor to
Change-A-Blade Corporation, New York, N. Y.,
a corporation of New York

Application September 17, 1943, Serial No. 502,745

1 Claim. (Cl. 30—260)

This invention relates to scissors having removable blades, and to means by which said blades may be readily and securely fitted on the blade-retaining elements.

One of the objects of the present invention is to provide a removable blade of the character described, preferably made by being stamped from relatively thin sheet metal in accordance with the manufacturing method disclosed in U. S. patent to William A. Zeidler, No. 2,177,414, and which shall be provided with means by which such a relatively thin sheet metal blade will be materially stiffened and made rigid to withstand cutting strains imposed upon it without becoming bent or distorted. The invention contemplates the provision of a turned-over reinforcement or flange extending along the rear edge of the blade and constituting a stiffening spine therefor.

The invention also contemplates an improved means for attaching the blade to its holder whereby the blade is held in a secure, non-shiftable relation to its holder, yet in such a manner as to permit speedy removal and replacement of the blade.

A still further object of the invention is to provide in a scissors, means by which the pivot pin may be adjusted easily and by which any set adjustment of said pin, and consequently the relative adjustment of the blades to one another, may be readily secured and indefinitely maintained.

These and other objects are accomplished by the invention, a more particular description of which will appear hereinafter and be set forth in the claim appended hereto.

In the accompanying drawing, forming a part hereof, Fig. 1 is a front elevation of a scissors constructed in accordance with the invention; Fig. 2 shows the opposite face of the scissors, with the scissors in open position; Fig. 3 is an edge view of the scissors; Fig. 4 is a sectional view on the line 4—4 of Fig. 1, looking in the direction of the arrows; Fig. 5 is a sectional view on the line 5—5 of Fig. 1, looking in the direction of the arrows; Fig. 6 is a sectional view on the line 6—6 of Fig. 2; Fig. 7 is a view looking at the inside face of one of the handle members; Fig. 8 is a face view of one of the detachable blades; Fig. 9 is an edge view of one of the blades; Fig. 10 is a face view of a section of sheet metal of curved conformation, showing how the scissor blades are cut obliquely therefrom, and Fig. 11 is an edge view of said section of metal.

The improved scissors is composed of two body

portions herein termed "handle members," 2 and 3, a pivot pin 4, and the two detachable blades 5, one of each of said blades being detachably secured to each handle member in the manner hereafter set forth. Each handle member is provided with the conventional finger hole 6 by means of which these members are engaged to enable the scissors to be operated in the known manner. Close to the pivot 4, each of the handle members 2 and 3 has a portion removed equal to the thickness of the blade 5, and this extends clear to the ends or pointed extremities 7 of the handle members.

As is well known, in ordinary scissors, it is necessary to give the cutting edges a peculiar shape and adjacent to these edges the scissors have warped or twisted surfaces. I attain this desired shape in the blades of the present invention by constructing them in the manner set forth in the Zeidler Patent No. 2,177,414 heretofore referred to.

Each of the blades is of tapering shape as disclosed in the drawing, and has a wider end or base 17 and a pointed extremity 18. Near the base 17 is provided a hole 8 through which the pivot pin 4 passes. Adjacent to the hole 8 is another and smaller hole 9 which closely fits around a small stud 10 projecting from the inside face 11 of one of the handle members. Nearer to the point or tip 18 of the blade is provided another small hole 12 which is drilled or punched diagonally through the blade. In other words, said hole 12 inclines upwardly or in a direction toward the tip of the blade, as will be clearly seen in Fig. 6. Adapted to engage and closely fit within the diagonal hole 12 is a diagonally extending stud 13 projecting from the inside face of the handle member. From the foregoing, the manner in which one of the blades is fitted onto a handle member will be readily understood. The hole 12 is first engaged with the diagonal stud 13 by sliding the blade 5 longitudinally toward the pivot opening in the handle member until the stud moves into the hole. This will serve to line up hole 9 with the stud 10 so that said stud will now engage with the hole. When the two blades have been applied to the handle members in the manner described, the pivot pin 4 is then inserted through the handle members and through the holes 8 in the two blades. Since the blades can only be detached from the handle members by longitudinal movement of said blades to thereby detach studs 13 completely from the holes 12, and since such longitudinal movement of the blades relative to the handle members is pre-

vented by the engagement of the pivot pin 4 with the holes 8, and also by the engagement of the studs 10 with the holes 9, it is obvious that the blades will be firmly secured to the handle members until it is desired to manually remove them. To do this, the pivot pin 4 is first removed. Then the blade is sprung laterally to an extent sufficient to disengage the stud 10 from the hole 9. Next the blade is slid longitudinally, or in a direction toward its tip, and this longitudinal movement of the blade will free the stud 13 from the diagonal hole 12 and thus completely free the blade from the handle member.

In the manufacture of the blades, a sheet of metal 14 is employed, said sheet being curved as indicated in Fig. 11. The blades are cut obliquely from this curved sheet, leaving openings therein substantially as shown at 15. Since each blade is cut from an arched or curved sheet and at an angle thereto, the resultant blade is not only slightly arched longitudinally but the blades have a slight desirable transverse twist. This arched and twisted arrangement of the blades, secured in each blade by the manner in which the blade is cut from the sheet, as distinguished from being formed by grinding of the blade, causes the two co-operating blades to be held in perfect shearing relationship. It also insures the uniformity of all blades.

As the blades are stamped out from relatively thin sheet metal, it is desirable that each blade shall be reinforced or stiffened. I attain this reinforcement by providing a stiff spine on each blade, consisting of a turned-over flange 16, which extends along the back edge of the blade for the length of the blade, or from the base 17 to the pointed end 18. It will be observed in Fig. 9 that said reinforcing flange, consisting of a part of the blade bent at right angles to the plane of the blade, gradually narrows in width from the base 17 of the blade to the pointed tip 18 thereof. It will be further noted that when the blades are fitted to the handle members 2 and 3, the turned-over flanges 16 rest firmly against the longitudinal edges 19 of the handle parts, this engagement of the blades with said parts acting to materially stiffen and strengthen the blades. It will also be noted from Figs. 4 and 5, that the width of each of the flanges 16 is no greater than the thickness of the handle parts against which these flanges are disposed, so that a smooth, tapering effect is obtained by the fitment of the blades against the handle parts in the manner described.

The pivot pin 4 consists of a simple threaded stud which freely passes through an unthreaded

hole 20 in one of the handle members, and is threadably received in an internally threaded hole 21 in the second handle member. The hole 20 is counter-sunk as indicated at 22 to receive the head 23 of the pin. As will be noted in Figs. 2 and 7, the threaded hole 21 has lateral slot extensions in the form of the lengthy oppositely disposed slots 24 and 25. The parts of the handle members on opposite sides of these slots may be sprung by the entry of the stud 4 thereinto, so that the threaded hole 21 may be made slightly undersize. As a result the threads in hole 21 will bind slightly on those of the stud so that the stud can only be turned within the hole 21 by the exertion of some manual force. Through this arrangement, the adjustment between the two blades of the scissors can be regulated and consistently maintained. The threaded hole 21 engages the threads 15 on the pivot pin with sufficient friction to prevent rotative movement of the pivot pin during normal cutting use of the scissors. However, when it is desired to change the clearance between the blades, a screw driver engaging the 20 slot in the head 23 of the pivot pin can overcome the frictional resistance of the threads in the hole 21 on those of the pivot pin and enable the pin to be manually turned in the desired direction to permit of precise adjustment of the blades.

While I have shown an embodiment of the invention, it is obvious that the same is not to be restricted thereto, but is broad enough to cover all structures coming within the scope of the annexed claim.

What I claim is:

A scissor having a detachable blade, said scissor having a handle part provided with a pivot-pin opening, a shank formed integrally with the 40 handle part and extending from the pivot-pin opening toward the tip of the blade but terminating at a distance from said tip, a detachable blade removably secured against a face of the shank, the blade being of tapered form and extending 45 beyond the end of the shank and having a bent-over flange extending along its rear edge only and at right angles to the body of the blade, the shank extending over and covering one face of the blade for the greater part of the length of 50 the blade with a part of the blade extending beyond the shank to form a relatively sharp point, said blade being stiffened by the shank, the shank having a flat edge disposed against the flange of the blade and having its opposite edge tapering 55 toward the cutting edge of the blade.

MAURICE L. COHN.
